INVENTOR

GEORGE McD. JOHNS,

by Ralph Koenig ATTORNEY.

UNITED STATES PATENT OFFICE.

GEORGE McD. JOHNS, OF ROCKDALE, TEXAS.

RETO RT.

Application filed November 12, 1923. Serial No. 674,376.

This invention relates to retorts generally and, more particularly, to a certain new and useful improvement in retorts of the type adapted especially for the treatment of materials, such as, for instance, oil-shale, lignite, peat, and coal, carrying a percentage of volatile matter, for obtaining the volatile content or residue thereof.

My present invention has for its chief object the provision of a retort of the type stated whereby the volatile content or residue of materials of the class mentioned may be economically, efficiently, thoroughly, and substantially completely driven off or obtained and later suitably recovered for utilization.

In the accompanying drawings,

Figure 1 is a broken vertical sectional view of a retort constructed in accordance with and embodying my present invention;

Figure 2 is a cross-sectional view of the retort; and

Figures 3, 4, and 5 are, respectively, detail fragmental plan, front, and edge views, the near frame-member in the latter view being omitted, of the cellular vapor-outlet providing wall of the treating-chamber of the retort.

Referring now more in detail and by reference characters to said drawings, which illustrate a preferred embodiment of my invention, the retort as a whole is a substantially vertical or upright structure of suitable dimensions and includes a body proper or shell A comprising a base wall 1, a furnace or fire-box 2, a main front wall 3, laterally spaced side walls 4, 4, and an arched top wall 5 preferably of refractory brick or other suitable masonry. Disposed upon the corners of the body or structure A, are re-enforcing angle-members or bars 6, suitably fixed to which, are additional angle-members 7 for receiving the ends of lateral or cross tie-bars 8 for rigidly staying the structure, as best seen in Figure 2. Enclosing and further supporting the structure A, is a preferably structural steel frame B, which may carry any auxiliary apparatus, as shown, suitable in the operation of the retort, and which is preferably topped with a suitable roof 9. Extending laterally between and fixed at their ends in the side walls 4 at the rear of the structure A in

a spaced vertical series, are angle-members or bars 10, for purposes shortly appearing; 55 and disposed within the structure and presented rearwardly from front wall 3 midway the side walls 4, is a flue or chamber dividing tile-wall 11.

Supported at its base on a bridge 12 forming part of base-wall 1 and extending vertically of the structure between the side walls 4 to the arch 5 and upon the rear end of wall 11, as best seen in Figures 1 and 2, is an upright refractory wall 13 composed preferably of carborundum plates or tile for their heat-conducting properties. This wall 13 is smooth and plane upon its opposite surfaces and particularly upon its rear face and divides the interior of the 70 enclosure of the retort formed by the front-wall 3, side walls 4-4, and rear cross-members 10 into a hot-gas flue or so-called heating-chamber 14 and the oven proper.

The flue or chamber 14 has communication, as at 15, at its lower end with the firebox 2, and at its upper end has exhaust or discharge for the products of combustion through an opening 16 in wall 3 leading to a stack 17. I might here state that the furnace 2, which may be fired with any suitable fuel, is preferably fired by pulverized fuel and the gases generated from the retort, which are fed into the furnace through an inlet 18 from a blower-fan 19 located on 85 frame B directly over the furnace and, in turn, connected with a suitable fuel supply-hopper 20, the pulverized fuel being dropped through a suitable mouth or feeder 21 into the suction of the blower 19, where it is 90 mixed with the gas and air for combustion.

Arranged to extend vertically intermediate the side-walls 4, 4, rearwardly of the wall 13, is a wall C comprising a pair of oppositely disposed channel-bars or frame-members 22-22, the flanges of which are presented inwardly, and which are suitably tied together in spaced relation by cross-rods 23. Disposed intermediate the channels 22, is a plurality of preferably transversely 100 corrugated steel sections or plates 24 disposed vertically in a more or less imbricated series and preferably oppositely arranged or reversed the one to the other, as best seen in Figure 4, or otherwise spaced, to form 105 ports or passages open to the opposite faces

of the wall, the sections or plates 24 being angularly or obliquely disposed relatively to, and suitably fixed at their ends in, the channels 22, as best seen in Figure 1. As 5 so formed, the wall C may well be described as cellular in structure and divides the oven proper of the retort into a so-called treating-chamber 25 and a vapor-collecting-chamber 26, the several open-end cells of the wall C 10 providing continuously open upwardly and outwardly disposed vapor-outlets from the treating-chamber 25 into the vapor collecting-chamber 26.

The wall C is adjustably spaced and held 15 from the fixed wall 13 by means of strips of asbestos or other suitable material 27 to regulate the dimensions of chamber 25 and consequently also the thickness of the layer or stream of the material being treated or 20 operated upon, the wall C being rigidly, but removably for repairs, replacement, or adjustment, held and retained in the desired spaced relation from wall 13 by means of plates 28 and stay-bolts 29, which, in turn, 25 have connection with angle-members 30 anchored to the structure by through-bolts 31, as best seen in Figure 2.

Supported on frame-work B and leading 30 into the upper end of the gravity treating-chamber 25, is a material supplying hopper 32, and discharging or exhausting from the chamber 25 for the spent material is a preferably screw-conveyor 33.

Closing the upper end of the vapor-collecting-chamber 26, is a plate 34, and forming 35 the rear wall of the chamber 26 and also of the structure A is a series of plates 35 preferably covered with heat insulation material, as shown, and detachably bolted to 40 the fixed cross members or channels 10.

Leading from the vapor chamber 26, through the plates 35, to suitable condensers, not shown, are one or more outlet-pipes 36. Of such outlets, I here show but one, but 45 it will be understood that more than one such outlet may be equally well provided, and that where more than one such outlet is provided, the collecting chamber 26 may be divided by horizontal partitions, also not 50 shown, into separate chambers for separating the vapors of different temperatures driven or distilled off from the material being operated upon or treated in chamber 25.

In use and practice, material of the class 55 mentioned to be treated or retorted is first suitably broken up into a finely divided or crushed condition, the degree of fineness or pulverization being preferably, say, twelve mesh. (The very fine part of the material, 60 say one hundred mesh and finer, resulting from the crushing or pulverizing operation, is screened out and utilized as fuel.) The material in such condition is more readily flowable and acted upon by heat, with the 65 result that, when subjected to heat, substan-

tially complete distillation is effected, as more fully described in Letters Patent No. 1,423,527, issued to me under date of July 25, 1922.

The material, in such finely divided or 70 crushed condition, is suitably delivered into the hopper 32, from which it falls by gravity into the chamber or space 25 provided between the smooth wall 13 and the cellular wall C. By reason then of the restricted 75 dimensions of the chamber 25 and the peculiar construction of the chamber-forming and vapor outlet-providing wall C, the material now flows or passes downwardly through chamber 25 in a substantially continuous 80 layer or stream of substantially uniform thickness to the bottom of the chamber, where the spent material or residue is removed or discharged by the conveyor 33. While so flowing downwardly in the chamber 25, it is subjected to the heat of the flat 85 smooth chamber-wall 13 imparted thereto by the products of combustion of fire-box 2 exhausting through the heating-chamber 14 and the stack 17, and the volatile content of 90 the material driven off, such volatile matter finding ready escape into the vapor collecting chamber 26 through the open cells or outlets of the wall C.

In such manner the material being treated 95 flows downwardly by gravity in the treating chamber 25 in a continuous stream or layer, yet one side or wall of the treating-chamber 25 is practically open for the escape of the 100 educed vapors of the treating-chamber. At the same time, while the cells of the wall C allow or permit the free escape of vapors from the entire surface of the layer of material so flowing or falling in the chamber, the obliquely disposed plates or sections 24 105 of wall C do not allow the material itself to escape from the chamber, but, on the contrary, constantly direct and hold the material against the heated plane surface or wall 13.

In such connection, I may add, the 110 width of chamber 25 being restricted, as described, and the column of flowable material being hence relatively small, the friction of the flat wall 13 and the cellular wall C, plus the successive shelf-like support afforded by 115 the presented lower side-end portions of the obliquely-disposed plates or sections 24 of the cell-wall C, oppose the head or weight of the flowing column of material as to prevent any possible flow of such fine material uphill out of the cell-openings of the wall C. It will be evident also that, by reason of the corrugated and hence sinuous form or surface contour of the successive 120 wall sections 24 and the opposed or reversed disposition or arrangement of the several plates of the series, the material being treated, in flowing or falling in the chamber 25 and successively upon the presented lower 125 side-end portions of the several plates 24, 130

shifts laterally of the chamber, that is to say, the material falling upon the crown of a corrugation of a particular plate shifts or flows therefrom under gravity into the laterally adjacent hollows of such plate, then from such hollows falls upon the crown of the next adjacent and opposed or reversed lower plate, then similarly shifts or flows into the hollows laterally adjacent to such latter crown, and so on throughout the series of plates and the travel or fall of the material through the retort, and thus a mixing of the material is effected as its flows downwardly, all of which actions combine in a resulting approximately complete distillation of the material being treated.

I am aware that changes in the form, construction, arrangement, and combination of the several parts of the retort may be made and substituted for those herein shown and described without departing from the nature and principle of my invention.

Having thus described my invention, what I claim and desire to secure by Letters Patent is:

1. In a gravity feed retort, a treating-chamber including a wall comprising a series of obliquely disposed corrugated plates forming vapor outlet-providing cells.
2. In a gravity feed retort, a treating-chamber including a wall comprising a series of corrugated plates disposed in obliquely parallel and opposed relation forming vapor outlet-providing cells.
3. In a gravity feed retort, a treating-chamber including a wall comprising a series of rectangular plates transversely corrugated and arranged in obliquely parallel and opposed relation forming vapor-outlet-openings.
4. In a gravity feed retort, a treating-chamber including a wall comprising a pair of spaced parallel frame-members and a series of rectangular transversely corrugated plates supported at their opposite ends by the frame-members, said plates being disposed in obliquely parallel and opposed relation forming vapor outlet-providing cells.
5. In a retort, a treating-chamber including a pair of spaced vertically disposed walls, one of said walls being smooth and imperforate and the other of said walls comprising a series of obliquely upwardly and outwardly presented corrugated plates forming vapor outlet-providing cells.
6. A gravity feed retort including a heating-chamber, a vapor-collecting-chamber, and an intermediate treating-chamber, the latter being separated from the heating-chamber by an imperforate wall and separated from the collecting-chamber by a second wall comprising a series of rectangular transversely corrugated vapor-outlet-providing plates.
7. A gravity feed retort including a heat-

ing-chamber, a vapor-collecting-chamber, and an intermediate treating-chamber, the latter being separated from the heating-chamber by an imperforate wall and separated from the collecting-chamber by a second wall comprising a series of rectangular transversely corrugated plates reversed the one to the other and providing vapor outlets into the collecting-chamber.

8. A corrugated feed retort including a heating-chamber, a vapor-collecting-chamber, and an intermediate treating-chamber, the latter being separated from the heating-chamber by an imperforate wall and separated from the collecting-chamber by a second wall comprising a series of rectangular transversely corrugated plates reversed the one to the other and providing vapor outlets into the collecting-chamber, said latter wall being movable toward and from the first wall for regulating the thickness of the layer of material being treated.

9. In a retort, a treating-chamber including a fixed wall, a second wall adjustably movable relatively to the fixed wall for regulating the thickness of the layer of material being treated and comprising a connected series of spaced vapor-outlet providing plates, and means for rigidly retaining the second wall in adjusted position relatively to the fixed wall.

10. In a gravity feed retort, a treating chamber including an imperforate fixed heating wall, a second wall comprising a series of obliquely upwardly-and-outwardly presented plates forming vapor-outlet cells, the second wall being adjustably movable relatively to the fixed wall for regulating the thickness of the layer of the falling material being treated, and means for retaining the second wall in adjusted position relatively to the fixed wall.

11. In a gravity feed retort, a treating-chamber including a wall comprising a plurality of rectangular transversely-corrugated plates disposed obliquely upwardly and outwardly in a spaced imbricated series and each presenting a sinuous surface to the falling material being treated in the chamber.

12. In a gravity feed retort, a treating-chamber having a wall comprising a plurality of rectangular transversely corrugated plates disposed obliquely upwardly and outwardly in a spaced imbricated series, reversed the one to the other, and each providing a sinuous surface to the falling material being treated in the chamber.

13. An upright gravity feed retort for finely divided flowable material having no definite angle of repose including a shell and walls within the shell dividing the same into a heating-chamber, a vapor-collecting chamber, and an intermediate treating-chamber, the wall separating the heating and treating chambers being flat and imperforate and the

wall separating the treating and vapor collecting chambers being parallel to and spaced from the first wall and comprising a plurality of rectangular transversely corrugated plates disposed obliquely upwardly and outwardly in a spaced imbricated series and reversed the one to the other, said plates providing vapor-outlets from the treating chamber and retaining the material being treated in an approximately vertical thin 10 layer against the heated wall.

In testimony whereof, I have signed my name to this specification.

GEORGE McD. JOHNS.
